UNITED STATES PATENT OFFICE.

GUSTAVUS A. SCHLECHTER, OF READING, PENNSYLVANIA.

DESIGN FOR A SPOON.

SPECIFICATION forming part of Design No. 22,033, dated December 6, 1892.

Application filed September 13, 1892. Serial No. 445,806. Term of patent 7 years.

To all whom it may concern:

Be it known that I, GUSTAVUS A. SCHLECHTER, a citizen of the United States, residing at Reading, in the county of Berks, State of Pennsylvania, have invented a certain new and original Design for Spoons, of which the following is a specification.

The main feature of my design for the handle of a spoon or similar article consists of the circular disk shown at the enlarged end of the handle, said disk having represented thereon a spray of flowers bound together by a fantastically-twisted ribbon arranged to form a series of ornamental letters. The portion of the handle between the enlarged end and the bowl is provided with scrollwork ornamentation.

A represents the circular disk provided upon the upper surface of the enlarged end

of the handle, beyond which extends an irregularly outlined and ornamented portion B.

C represents a spray of forget-me-nots appearing upon the surface of the disk, and D a fantastically-twisted ribbon arranged to bind together the stems of the flowers and also to form a series of ornamental letters. The scroll ornamentation E upon the intermediate portion of the handle extends from the disk A toward the bowl of the spoon.

What I claim is—

The design for the handle of a spoon or similar article, substantially as shown.

In testimony whereof I affix my signature in presence of two witnesses.

GUSTAVUS A. SCHLECHTER.
